UNITED STATES PATENT OFFICE.

DE WITT B. HARVEY, OF TROY, PENNSYLVANIA.

HALTER-TRIMMING.

SPECIFICATION forming part of Letters Patent No. 374,832, dated December 13, 1887.

Application filed December 7, 1886. Serial No. 220,937. (No model.)

To all whom it may concern:

Be it known that I, DE WITT B. HARVEY, a citizen of the United States, residing at Troy, in the county of Bradford and State of Pennsylvania, have invented a new and useful Improvement in Stationary-Web Halters, of which the following is a specification.

My invention relates to an improved corner clasp or trimming for web halters.

10 The invention will first be described and then claimed.

In the drawings, Figure 1 is a side or perspective view of halter, showing clasp put together as in finished halter, the webbing being 15 inclosed by plates A and B and riveted together by rivet C, rivet C passing through plate B, thence through the three thicknesses of folded web at junction of headstall and nose-piece, thence through plate C, and riveted, 20 making an inclosed clasp for web, as plate A, Fig. 1; just fits inside the flanges F, Fig. 2, on plate B.

Fig. 2 is an inside view of plate B, with web 25 as folded inside flanges F to receive plate A, and all held in place by rivet C, passing through hole E, as shown in Fig. 3. Loop G, at corner of plate B, Fig. 2, is integral with plate B—not a separate piece, but cast solid with plate B. Dotted line *xx* in Fig. 2 represents an indicated cutting in section, as shown in Fig. 3, (sectional view,) and shows where Fig. 2 is 30 cut to give the sectional or edgewise view of clasp and web riveted together, as shown in Fig. 3.

Fig. 3 is a view in section of or edgewise 35 view of plate B, with web D as folded inside flanges F, as shown in Fig. 2, plate A next being laid on fold of web D, both of which are held in place by flanges F, Fig. 2, on plate B, then riveted together by rivet C, passing 40 through hole E, as shown in Fig. 3, the rivet C passing through plate B, thence through the three thicknesses of web as folded at junction of cheek-pieces or headstall and nose-piece, thence through plate A, (inside flat plate,) 45 and riveted, making a very rigid and inclosed clasp for web. D designates one single piece of web, which forms the headstall, cheek-pieces, and nose-piece.

Having fully described my invention, what 50 I claim, and desire to secure by Letters Patent of the United States, is—

The herein-described corner clasp for halters, the same consisting of the plate provided with angular external and internal flanges to cover 55 the edges of the halter-webbing and having an integral loop or ring extending diagonally from its outer corner, and a plate designed to fit inside the flanges, said two plates adapted to be secured together and to the halter-webbing by a rivet passing through the fold in the webbing and through the plates, substantially as described.

DE WITT B. HARVEY.
